UNITED STATES PATENT OFFICE.

LEWIS H. STONER, OF ALBANY, INDIANA.

CEMENT POST.

SPECIFICATION forming part of Letters Patent No. 762,008, dated June 7, 1904.

Application filed October 1, 1902. Serial No. 125,485. (No model.)

To all whom it may concern:

Be it known that I, LEWIS H. STONER, of Albany, county of Delaware, and State of Indiana, have invented a certain new and useful 5 Cement Post; and I do hereby declare that the following is a full, clear, and exact description thereof, reference being had to the accompanying drawings, in which like numerals refer to like parts.

10 The object of this invention is to make a post for fences or other purposes that is very cheap and quite strong and durable. The object is accomplished by molding a cement post in the ground and molding in it and with it 15 suitable braces and reinforcing metal frames and molding it with suitable holes for fence-wires as well as brackets for gates extending from it.

10 The nature of the invention will be understood from the following description and claims, together with the accompanying drawings.

20 In the drawings, Figure 1 is a perspective of the post in place. Fig. 2 is a vertical section through the same as molded into the ground. Fig. 3 is an elevation of the reinforcing-frame within the post.

25 In detail a wire-fence anchor-post is shown, 10 being the ground, and 11 the cement post 30 molded in the same, and 12 is a cement brace integrally connected with the post and with its base enlarged and also molded into the ground. The post is provided with transverse holes 13 for fence-wires to extend through, 35 which are on one side of the vertical center line of the post. The brace is secured to the post centrally on a side having said series of holes and to one side of them. These are 40 preferably made while the post is being molded by removable rods in the molding.

45 14 represents gate-brackets that are preferably placed in the post while it is being molded. A metal frame 15, formed of parallel pipes united at different points, is embedded in the post while it is being molded so 50 one pipe of said frame will be on each side of the series of holes, as is shown. This increases the strength and durability of the post. It preferably extends down into the bottom of

the post and beneath the ground. The brace 55 12 is likewise reinforced by the pipe or other metal frame 16 that is embedded in the cement brace while it is being molded. Its upper end extends into about the middle of the post and maintains the union between the 60 brace and the post, as well as preserves the rigidity of the brace throughout its length. The upper end of the metal brace-frame 16 is turned downward to strengthen the position of such metal frame in the main post, and it 65 may be caught over a portion, such as the cross-bar 17, of the metal frame 15.

70 This post may be molded into any ornamental design to be used for any purpose. If part of the cement forming the brace should 75 be knocked off, the pipe 16 still acts as a brace and the cement part of the brace can be readily repaired with new cement. The same is true of the post if it should be accidentally struck by a wagon-wheel or other thing. The 80 result is that the post may be made beautiful and its design preserved, as well as be durable and strong. It is cheaper than wooden posts, because it can be so quickly molded in place. Its initial cost is less and its greater longevity 85 makes the total cost of it still less than a wooden post.

What I claim as my invention, and desire to secure by Letters Patent, is—

1. A post for fences formed of cement built 80 in and extending above the ground with a series of holes therethrough for fence-wires, and a brace for the post formed also of cement embedded at its lower end in the ground and integrally connected with said post above the 85 ground on a side thereof having in it said holes and to one side of said series of holes.

2. A post for fences formed of cement with transverse holes through it for the wires of a fence, a metal frame embedded in said post 90 with a cross-bar forming a part of said frame, a brace for said post formed also of cement integrally connected with the post, and a metal frame embedded in said brace with one end extending into said post and engaging the 95 cross-bar of the metal frame in said post.

3. A post for fences formed of cement with a series of transverse holes through it to one

side of the vertical center line of the post for
the wires of a fence, a metal frame embedded
in the cement having two vertical parallel
bars, one on each side of said series of holes,
5 and a brace for said post formed also of cement
integrally connected with the post centrally
to one side of the series of holes.

In witness whereof I have hereunto affixed
my signature in the presence of the witnesses
herein named.

LEWIS H. STONER.
